(57) **CLAIM**

The ornamental design for sprinkler irrigation device, as shown.

DESCRIPTION

FIG. 1 is a perspective view as seen from the front and left of a sprinkler irrigation device according to the present invention;

FIG. 2 is a left side view of the embodiment;

FIG. 3 is a right side view of the embodiment;

FIG. 4 is a top view of the embodiment;

FIG. 5 is a bottom view of the embodiment;

FIG. 6 is a rear view of the embodiment; and,

FIG. 7 is a front view of the embodiment.
